US00D749610S

(12) **United States Design Patent**
Lee et al.

(10) **Patent No.:** **US D749,610 S**
(45) **Date of Patent:** **** Feb. 16, 2016**

(54) **DISPLAY SCREEN OR PORTION THEREOF
WITH GRAPHICAL USER INTERFACE**

(71) Applicant: **Samsung Electronics Co., Ltd.**,
Suwon-si, Gyeonggi-do (KR)

(72) Inventors: **Joo-Hyung Lee**, Seoul (KR); **You-Jin
Im**, Seoul (KR); **So-Ra Kim**, Seoul
(KR); **Hye-Bin Park**, Seoul (KR)

(73) Assignee: **SAMSUNG ELECTRONICS CO.,
LTD. (KR)**

(**) Term: **14 Years**

(21) Appl. No.: **29/478,613**

(22) Filed: **Jan. 7, 2014**

(30) **Foreign Application Priority Data**

Sep. 3, 2013 (KR) 30-2013-0045432

(51) **LOC (10) Cl.** **14-04**

(52) **U.S. Cl.**

USPC **D14/486**

(57) **CLAIM**

We claim the ornamental design for a display screen or portion thereof with graphical user interface, as shown and described.

DESCRIPTION

The FIGURE is a front view of a display screen or portion thereof with graphical user interface showing our new design. The broken lines illustrating portions of the display screen or portion thereof with graphical user interface are for environmental purposes only and form no part of the claimed design.
